UNITED STATES PATENT OFFICE.

HERBERT M. LOFTON, OF CHATTANOOGA, TENNESSEE.

FIRE-HYDRANT.

1,178,588.

Specification of Letters Patent. Patented Apr. 11, 1916.

Application filed August 24, 1910. Serial No. 578,774.

To all whom it may concern:

Be it known that I, HERBERT M. LOFTON, a citizen of the United States, and a resident of Chattanooga, county of Hamilton, 5 State of Tennessee, have invented an Improvement in Fire-Hydrants, of which the following is a specification.

My invention has reference to fire hydrants and consists of certain improvements 10 which are fully set forth in the following specification and shown in the accompanying drawings which form a part thereof.

The object of my invention is to provide a suitable construction of fire hydrant which 15 will permit the seat ring of the main valve together with the main valve and drainage valve devices to be conveniently removed from the shoe and stock when necessary for repairs or otherwise, and more particularly my improvements are directed to the 20 manner of securing the seat ring in position whereby it may be easily removed when desired.

My invention consists of certain features 25 of construction for securing the above mentioned and other objects of invention and which features of construction are fully described hereinafter and particularly defined in the claims.

30 My improvements will be better understood by reference to the drawings in which:—

Figure 1 is a sectional elevation of a fire hydrant embodying my invention; Fig. 2 is 35 a cross section of the same on line $x-x$; Fig. 3 is a plan view of the seat ring removed; Fig. 4 is a sectional elevation of the seat ring upon line $s-s$ of Fig. 3; Fig. 5 is a cross section of the hydrant on line $z-z$ 40 of Fig. 1 made upon a larger scale; Fig. 6 is a cross section of the hydrant on line $y-y$ of Fig. 1; Fig. 7 is a view corresponding to Fig. 2 but showing a modified construction of seat ring; and Fig. 8 is a sectional elevation of the modified form of seat ring.

45 2 is the shoe having the inlet 3 and having its upper portion formed with a tubular aperture and horizontal flange.

4 is the stock of the hydrant and is flanged 50 at the bottom, and these flanges of the stock and shoe are bolted together as indicated at 5 in Fig. 1.

55 9 is a seat ring and is made annular and with a conical seat at the bottom for the main valve 16. The cylindrical outer surface near the upper part of the seat ring is

provided with an annular groove 11 from which extends inwardly a radial aperture 12 for draining the stock of water when the main valve is closed. The lower outer portion of the seat ring is shaped so as to provide an annular shoulder 9^a, the said shoulder being undercut, as will be readily understood by reference to Fig. 4. The annular seat ring 9 fits into a cylindrical portion of the aperture in the shoe which is arranged immediately above an annular inwardly directed flange 8 between which and the shouldered portion of the ring a gasket 21 of ductile metal may be clamped for forming a water tight joint. The inner surface of this cylindrical part of the shoe is preferably provided with an annular groove 6 which coöperating with the annular groove 11 of the seat ring provides a large annular 75 water drainage passage entirely around the seat ring. This water passage may be provided with one or more drainage apertures 7 leading through the shoe to the outside for permitting the waste water to drain from 80 the hydrant. The seat ring 9 has no screw threads upon its outer part for attaching it in the shoe so that it may be easily lifted from the shoe when it is desired to remove it for any cause. The seat ring is clamped 85 in position by means of clamping ring or bushing 10 which screws into the aperture in the shoe above the seat ring and presses down upon it to clamp the gasket 21 between said seat ring and the flange 8 of the 90 shoe. This bushing 10 may be provided with upwardly extending lugs 15 by which it may be turned when being screwed in or out of position.

95 It will be noted that the external diameter of the seat ring 9 is equal to or less than the internal diameter of the screw threaded portion of the shoe so that the said seat ring is not interfered with by the screw threads. It will also be noted that the seat ring is not 100 required to be rotated during the rotation of the clamping ring or bushing and consequently there is no injury to the packing gasket 21 such as would be liable in case of the rotation of the seat ring. Furthermore, 105 as the screw threaded portion to be unscrewed is considerably less than would be the case if the screw threads extended downward upon the seat ring, there is not as much resistance to the removal of the clamping ring and seat ring as is the case in those 110 structures where the seat ring and bushing

are in one integral piece and screwed into the shoe.

The undercut shoulder 9^a of the seat ring causes the gasket to become attached to the seat ring after the latter has been clamped into position within the shoe so that when the seat ring is removed, the gasket is drawn up with the seat ring instead of remaining in the stock or becoming injured by partly adhering to the stock and partly to the seat ring. This is an important feature in that it removes all difficulty with respect to the repacking of the seat ring when the hydrant is in place in the ground.

16 is the main valve and is carried by the valve stem 20 which is raised and lowered by the wrenched nut and sleeve 22 carried by the head 4^a of the hydrant stock. The main valve seats upon the conical seat at the bottom of the seat ring and is provided with a top plate having two upwardly directed guide wings 18, one of which may be provided with a packing strip 19. These guide wings 18 are guided in vertical guide grooves or notches 13 upon the inner surface of the annular seat ring and the distance across between the outer surfaces of the wings is approximately equal to the internal diameter of the clamping ring or bushing 10 so that the latter may be rotated without rotating the main valve. The radial drainage aperture 12 opens into one of these guide notches 13 so that the packing strip 19 of the guide wing 18 may coöperate with said aperture to seal it whenever the main valve is lowered. In the position shown in Fig. 1, the main valve is closed and the water may drain from the stock 4 around the head 17 and the wing 18 and out by the drainage aperture. When the main valve is lowered to a slight extent, the radial drainage aperture 12 is sealed and remains sealed until the main valve is again closed upon its seat.

In those cases where there are a plurality of nozzles 23 and 23^a opening from the stock, it is customary to provide shut-off valves so that the hydrant may be employed with one or more nozzles or operation and also to permit the adding or removing of one or more lines of hose without interfering with the remaining nozzles in connection with the performance of their function. I have shown the nozzle 23^a of smaller diameter than the nozzle 23, but this is not essential. Referring to the specific construction employed in these cut-off valves, I so form the brass nozzles 23 that their inner ends 28 are flanged and form flat seats for the cut-off valves 29 which are arranged upon the inside of the stock. These nozzles 23 extend through apertures in the stock and are held in position by metal packing 27 arranged in an annular groove 24 about the nozzle and formed on the stock itself. This packing 27 is introduced after the nozzle 23 has been placed in position in contact with the closed cut-off valve 29 so that it will be retained in proper position to coöperate with said valve 29 while permitting the latter to be raised or lowered at will. The cut-off valve 29 is a gate valve and is guided in vertical guide ways 32 upon the inside of the stock, and has at each side of its rear, inclined guide surfaces 26 which coöperate with corresponding inclined guides 25 forming the lower part of the vertical parts 32. When the valve is down, the inclined guides 25 force it against the seat 28 of the nozzle 23, as will be readily understood. The valve 29 is raised and lowered by means of a screw threaded shaft 30 working in a screw threaded aperture 31 in the shut-off valve 29 and this screw threaded stem is provided at the top with an annular collar 33 and a wrench receiving terminal 35. The collar 33 rests upon a shoulder in the upper part of the head 4^a and is clamped down by an annular bushing nut 36. Packing 34 below the collar provides a water tight joint. By rotating the shaft 30, the gate or cut-off valve may be raised or lowered and operated independently of the main valve. Each of the several nozzles have their own individual cut-off valve and consequently the description above given will apply to each of them. The guides 32 and 25 are cast in with the hydrant stock or barrel, as will be understood by reference to Fig. 5, thereby avoiding expensive machine work. As the nozzles 23 are adjusted to the valves 29 when lowered and in the custody of the guides, it is evident that the necessity for making very accurate guides is overcome and subsequently the expense of providing the cut-off valves is materially reduced.

Instead of providing the seat ring 9 with the annular groove 11 and also providing an annular groove 6 in the stock, these parts may be simplified, as indicated in Figs. 7 and 8 in which the annular groove in the seat ring is omitted and a vertical groove 41 provided instead. This modified seat ring 9^a is then dropped into position within the shoe and is required to assume a proper circumferential radial drainage aperture 12 with respect to the drainage aperture 7 in the shoe by means of a pin 40 which is driven through the shoe, as indicated in Fig. 7 and which provides a guide to receive the groove 41 so that the seat ring cannot take any but the proper position. This construction is somewhat less expensive than the construction shown in Figs. 1 to 4, but also embodies the advantageous feature of the seat ring being separate from the clamping bushing and which is the more essential part of my invention.

In this application, I do not claim the construction of the discharge nozzles or valves therefor, as the same will form sub-

ject matter of a separate application. Neither do I claim in this application the feature of the undercut portion 9^a of the valve seat ring with the gasket 21 which becomes 5 permanently attached in the undercut portion by the clamping action in assembling the valve, and whereby it becomes removable with the seat ring, as said construction will also form the subject-matter of a separate application.

I have shown my invention in the form which I have found excellently adapted in commercial practice to the purposes thereof, and while I prefer the details here shown, I 15 do not limit myself thereto, as they may be modified without departing from the spirit of the invention.

Having now described my invention, what I claim as new and desire to secure by Letters Patent is:—

1. In a fire hydrant, a shoe having at its upper end a cylindrical aperture, and a stock secured to the shoe, combined with a valve seat ring secured to the cylindrical aperture 25 of the shoe and having at the bottom a valve seat and also provided on its inner vertical surface with vertical guide notches extending the full height of its inner surface and down to the seat said notches presenting lateral parallel shoulders wholly outside of the 30 diameter of the tubular water passage, and also having a drainage aperture through the vertical wall of one of the notches and intermediate of its upper and lower notches, 35 a valve below the seat ring and means to vertically reciprocate it, and vertical guides fitting into the guide notches of the seat ring and movable with the valve and its operating means said guides acting to guide 40 the main valve and prevent its rotation and one of said vertical guides also acting as a drainage valve for the drainage aperture.

2. In a fire hydrant, a shoe having at its upper end a cylindrical aperture provided 45 at its lower part with an annular flange and at its upper part with an internal screw threaded portion of larger internal diameter and also with a drainage passage through its unthreaded portion, combined with a 50 seat ring having its body fitting the cylindrical aperture between the annular flange and the screw threaded portion and having a vertical guide groove on its inner surface and a radial drainage port opening into 55 said groove, and said seat ring also provided with a downward annular portion extending into the flange and having a conical valve seat on its lower part, a gasket between the seat ring and annular flange of the shoe, a clamping bushing in the form of a flangeless ring of uniform diameter screwed into the screw threaded portion of the aperture of the shoe without restriction except by the seat ring said bushing pressing down upon the seat ring to clamp it

upon the gasket, a main valve below the seat ring and seating upwardly upon the valve seat on the bottom part of the same and provided with a sliding drainage valve fitting the vertical groove in the seat ring and directly controlling the radial drainage port, a stock secured to the shoe inclosing the bushing and seat ring and wholly independent of them, and a valve stem to operate the valve extending from the stock downwardly through the bushing and valve seat.

3. In a fire hydrant, a shoe having at its upper portion a cylindrical aperture provided with an annular shoulder at the bottom having substantially right-angled walls, 80 combined with a valve seat ring fitting the cylindrical aperture and having its bottom provided with an annular shouldered and grooved portion and its inner face provided with guide notches, a non-elastic gasket embedded in and secured to the annular shouldered and grooved portion of the seat ring so as to be lifted with the seat ring when it is withdrawn from the shoe, a flangeless clamping bushing screwed into the upper 90 portion of the cylindrical aperture in the shoe for clamping the seat ring down upon the bushing, and a valve seating upon the seat ring and having guide wings guided in the guide notches of the seat ring.

4. In a fire hydrant, a shoe having at its upper end a cylindrical aperture said aperture provided at its lower part with an annular flange and at its upper part with an internal screw threaded portion of larger 100 internal diameter, and a stock for the shoe combined with an annular seat ring snugly fitting the cylindrical aperture between the annular flange and screw threaded portion and having vertical guide notches upon its 105 inner surface, a flangeless clamping bushing wholly independent of the stock screwed into the screw threaded portion of the aperture and pressing down upon the seat ring, and a main valve seating upon the under side of the seat ring and having guide wings guided in the guide notches on the seat ring.

5. In a fire hydrant, a shoe having at its upper end a cylindrical aperture said aperture provided at its lower part with an annular flange and at its upper part with an internal screw threaded portion of larger internal diameter, and a stock for the shoe combined with an annular seat ring snugly fitting the cylindrical aperture between the 115 annular flange and screw threaded portion and having vertical guide notches upon its inner surface one of which has a radial drainage port, a flangeless clamping bushing wholly independent of the stock screwed into the screw threaded portion of the aperture and pressing down upon the seat ring, and a main valve seating upon the under side of the seat ring and having guide wings guided in the guide notches on the 120

125

130

- seat ring one of said wings acting as a waste valve for the radial drainage port in the seat ring.
6. In a fire hydrant, a removable seat ring for the main valve having a ring shaped body cylindrical upon its outer surface and provided on said outer surface with an annular drainage groove and also having a radial drainage aperture through 10 the wall of the body into the annular drainage groove terminating in a vertical guide groove and further having its lower inner surface made conical to provide a valve seat and its outer surface furnished with a vertical slot.
7. In a fire hydrant, the shoe having an aperture at its upper portion said aperture formed with a cylindrical lower portion and a screw threaded upper portion, combined
- with a stock secured to the shoe, an annular valve seat ring fitting the cylindrical lower portion of the aperture in the shoe and provided with guide notches upon its inner surface said seat movable from the shoe without turning, a flangeless clamping bushing wholly independent of the stock and screwed into the screw threaded upper portion of the aperture in the shoe to hold the seat ring in position, and a valve piece seating upon the under portion of the seat ring and having parts guided by the guiding notches thereof.

In testimony of which invention, I hereunto set my hand.

HERBERT M. LOFTON.
